ROTARY PUMP

Irving C. Jennings, South Norwalk, Conn.

Application January 19, 1934, Serial No. 707,350

7 Claims. (Cl. 103—96)

The object of this invention is to provide a new and improved rotary liquid pump, particularly adapted for pumping liquids at high pressure.

- 5 To this end the pump comprises a casing having a chamber, a rotor turning therein and having peripheral buckets, and an inlet and outlet for directing the liquid peripherally to and from said buckets.
- 10 The chamber is shaped so that the rotor will fit closely to a portion thereof, preferably a minor portion, and loosely to another portion thereof, preferably a major portion, and the inlet and outlet are preferably arranged in the same plane.
- 15 By this construction a rotary pump is provided which can be operated efficiently with very little friction at high speeds to generate a very high pressure.

The pump is illustrated in the accompanying sheet of drawings, in which

Fig. 1 is a sectional elevation taken on the line 1—1 of Fig. 2, the cross matching of the rotor being omitted so that the parts at the rear thereof can be shown by dotted lines.

25 Fig. 2 is a sectional elevation taken on the line 2—2 of Fig. 2, and

Fig. 3 is an enlarged partial sectional elevation illustrating the operation.

Referring to the drawing and in detail, A designates a circular casing which has suitable feet or supports to form the base of the structure. A chamber is formed in the casing, this chamber having a major portion formed on one radius a and with a minor portion formed on a smaller radius a' , as shown in Fig. 1.

The base A is provided with arms B, which carry a bearing, preferably a ball bearing C. A face plate or cover D is fitted axially into the base A and secured thereto by bolts. The plate D is provided with arms E which carry a bearing F, preferably a ball bearing.

A rotor or impeller G is arranged in the casing and is keyed or secured on a driving shaft H, which is fitted in the ball bearings C and F. Stuffing boxes I and I' are arranged in the casing A and the face plate D to pack the shaft G tightly in the chamber. The rotor G is provided with forwardly pitched, preferably curved, blades J on its periphery, arranged between side partitions or shrouds K', thus forming peripheral buckets L. The bottoms of these buckets are made semi-cylindrical, as at L', on axes parallel to the axis of the rotor as shown in Fig. 2. Preferably, a large number of buckets is employed.

The rotor fits closely to the portion M of the circular chamber of small diameter. The casing is provided with a supply passage N which directs the incoming liquid into a passageway O, to a chamber P. The pump inlet Q extends from said chamber P and is arranged to direct the incoming liquid tangentially to the rotor.

An outlet R is arranged tangentially in the casing at about the point where the chamber changes from large diameter to small diameter so that the liquid will be discharged peripherally from the rotor.

A series of holes S S is bored through the rotor.

The operation is as follows, assuming that the rotor revolves in the direction indicated by the arrows in Fig. 1 and Fig. 3.

As the buckets pass the end of the section M of the chamber, water will be drawn into the pump casing through the peripheral inlet Q by the action of the curved blades scooping into the water, producing a forward rotating flow towards the outlet. The water is scooped or drawn into a bucket, advanced and discharged into the peripheral chamber, where it is again caught and whirled along by the pressure side of the succeeding bucket. This advances or forces the water around in the pump casing, each bucket adding to the pressure. The water rotates between the buckets of the rotor and the section of the chamber of large diameter and is finally delivered through the outlet passage.

As the bottoms of the buckets are made semi-cylindrical, this whirling action causes very little turbulence or friction.

The holes S S through the rotor or impeller G balance the same against any end thrust, if the water leaks unequally between the sides of the rotor and the casing. This does away with the need of tight fits between the sides of the rotor and the casing A and plate D. The only tight fit that has to be considered is that between the periphery of the rotor and the section M of the chamber, and by making this fit as close as possible without actual engagement of the parts, it will be noticed that the rotor can be driven with very little friction.

By arranging the inlet N and the outlet R in the manner shown, the pump can be put into a pipe line with very little pipe fitting.

The details and arrangements herein shown and described may be greatly varied by a skilled mechanic without departing from the scope of my invention, as expressed in the claims.

Having thus fully described my invention, what

I claim and desire to secure by Letters Patent is:—

1. In a rotary liquid pump, the combination of a casing having a circular chamber formed on a major section of larger diameter and a minor section of smaller diameter, a rotor turning therein and having peripheral buckets formed by forwardly pitched blades which bear peripherally only on the minor section, the bottoms of which buckets are made substantially semi-cylindrical on axes parallel to the axis of the rotor, whereby a circulation of liquid to and from each of the buckets is produced through the plane of direction of rotation of the rotor and an inlet and outlet for directing the liquid to and from said buckets.

2. In a rotary liquid pump, the combination of a casing having a circular chamber formed on a major section of large diameter and a minor section of smaller diameter, a rotor turning therein and having shrouds and peripheral buckets formed by forwardly pitched blades between said shrouds which bear peripherally only on the minor section, the bottoms of which buckets are made substantially semi-cylindrical on axes parallel to the axis of the rotor, whereby a circulation of liquid to and from each of the buckets is produced through the plane of direction of rotation of the rotor and an inlet and outlet for directing the liquid to and from said buckets.

3. In a rotary liquid pump, the combination of a casing having a circular chamber formed on a major section of larger diameter and a minor section of smaller diameter, a rotor turning therein and having peripheral buckets formed by forwardly pitched blades which bear peripherally only on the minor section, the bottoms of which buckets are formed with a pronounced curvature in the plane of rotation of the rotor, and an inlet and outlet for directing the liquid to and from said buckets, said inlet being so disposed as to direct the liquid into the chamber substantially at, and tangentially to, the periphery of the rotor in the direction of rotation.

4. In a rotary liquid pump, the combination of a casing having a circular chamber formed on a major section of large diameter and a minor section of smaller diameter, a rotor turning therein and having shrouds and peripheral buckets formed by forwardly pitched blades between said shrouds which bear peripherally only on the minor section, the bottoms of which buckets are formed with a pronounced curvature in the plane of rotation of the rotor, and an in-

let and outlet for directing the liquid to and from said buckets, said inlet being so disposed as to direct the liquid into the chamber substantially at, and tangentially to, the periphery of the rotor in the direction of rotation.

5. In a rotary pump, the combination of a pump chamber and a rotor revoluble therein, said chamber having a land of smaller diameter than that of the chamber and positioned to closely cooperate with the periphery of the rotor, said rotor having peripheral buckets formed by forwardly pitched blades which bear peripherally only on said land, the backs of said blades being forwardly curved adjacent their peripheral edges to create a reduction in pressure, the bottoms of which buckets are formed with a pronounced curvature in the plane of rotation of the rotor, and an inlet and outlet for directing the liquid to and from said chamber, said inlet being so disposed as to direct the liquid into the chamber substantially at, and tangentially to, the periphery of the rotor in the direction of rotation.

6. In a rotary pump, the combination of a pump chamber and a rotor revoluble therein, said chamber having a land of smaller diameter than that of the chamber and positioned to closely cooperate with the periphery of the rotor, said rotor having shrouds and peripheral buckets formed by forwardly pitched blades between said shrouds which bear peripherally only on said land, the backs of said blades being forwardly curved adjacent their peripheral edges to create a reduction in pressure, the bottoms of which buckets are formed with a pronounced curvature in the plane of rotation of the rotor, and an inlet and outlet for directing the liquid to and from said chamber, said inlet being so disposed as to direct the liquid into the chamber substantially at, and tangentially to, the periphery of the rotor in the direction of rotation.

7. In a rotary pump, the combination of a pump chamber and a rotor revoluble therein, said chamber having a land of smaller diameter than that of the chamber and positioned to closely cooperate with the periphery of the rotor, said rotor having peripheral buckets formed by forwardly pitched blades which bear peripherally only on said land, the backs of said blades being forwardly curved adjacent their peripheral edges to create a reduction in pressure, the bottoms of which buckets are made substantially semi-cylindrical on axes parallel to the axis of the rotor, and an inlet and outlet for directing the liquid to and from said chamber.
